UNITED STATES PATENT OFFICE.

CHARLES STOLZE, OF RHINELANDER, WISCONSIN.

WRENCH.

SPECIFICATION forming part of Letters Patent No. 498,321, dated May 30, 1893.

Application filed April 5, 1893. Serial No. 469,129. (No model.)

To all whom it may concern:

Be it known that I, CHARLES STOLZE, a citizen of the United States, residing at Rhinelander, in the county of Oneida and State of 5 Wisconsin, have invented a new and useful Wrench, of which the following is a specification.

The invention relates to improvements in wrenches.

10 The object of the present invention is to improve the construction of wrenches, and to provide one adapted for use either as a nut or pipe wrench, and capable when being used for the latter purpose of forming a perfect 15 pipe wrench.

The invention consists in the construction and novel combination and arrangement of parts hereinafter fully described, illustrated in the accompanying drawings and pointed 20 out in the claim hereto appended.

In the drawings—Figure 1 is a perspective view of a wrench constructed in accordance with this invention, and shown arranged as a pipe wrench. Fig. 2 is a longitudinal 25 sectional view. Fig. 3 is a detail perspective view of the pivoted sliding jaw.

Like numerals of reference indicate corresponding parts in all the figures of the drawings.

30 1 designates a shank rectangular in cross-section having a handle 2 at one end and provided at the other end with a stationary preferably integral jaw 3, which is adapted for nuts and which, when the wrench is employed for operating on pipes, has secured to it a steel jaw-face 4. The jaw-face is constructed with a hook 5 to engage the tapered end of the stationary jaw; and it is provided with opposite parallel flanges 6 ex- 35 tending on opposite sides of the shank and

40 projecting beyond the same and provided with openings receiving a pin 7 for securing the jaw-face in place. The engaging surface of the jaw-face is curved and provided with 45 shouldered teeth. The shank has mounted on it a sliding casing 8 adapted to be adjusted on the shank between the handle and the stationary jaw, and carrying at its upper end a pivoted jaw 9 which has its upper face

provided with a series of teeth or projections adapted to co-operate with those of the jaw-face. The sliding casing is secured in its adjustment by opposite similar pivoted pawls 10, which engage opposite teeth 11 of the shank and which are held in such engagement by flat springs 12. The pivoted jaw is provided at its lower side with a depending lug 13, which is perforated and pivoted in a recess 14 by a pin 15. The recess 14 is formed in the upper end of the casing, 60 which is provided thereat with an extension 16 arranged beneath the outer portion of the pivoted jaw for supporting the same. The pivoted jaw is provided at its inner side with parallel guiding flanges 17, which are disposed on opposite sides of the shank to prevent the jaw 9 having any lateral movement. The arrangement of the pivoted jaw 9 is such that in screwing or turning a pipe the tendency is to force the said pivoted jaw inward toward the shank, thereby lessening the distance between the jaws and clamping the jaws more securely; and in releasing the wrench the operation is reversed and tends to separate the jaws, thereby readily freeing 75 the wrench.

When employed as a nut wrench the jaw-face 4 is detached.

It will be seen that the wrench is adapted to be employed either as a nut or a pipe 80 wrench, and that when employed for the latter purpose it is especially adapted for such use.

Changes in the form, proportion and the minor details of construction may be resorted to without departing from the principle or sacrificing any of the advantages of this invention.

What I claim is—

In a wrench, the combination of a shank 90 having oppositely disposed teeth and provided at its upper end with a stationary jaw, a steel jaw-face detachably secured to the stationary jaw, a sliding casing mounted on the shank and provided at one side with an 95 upward and outward extension and having a recess at the inner side of the extension, spring actuated pawls pivotally mounted on

the casing and engaging the teeth of the shank, and a pivoted jaw provided with a depending lug secured in the recess of the casing by a pin, and provided at its inner side with parallel guide flanges arranged on the sides of the shank, substantially as described.

In testimony that I claim the foregoing as my own I have hereto affixed my signature in the presence of two witnesses.

CHARLES STOLZE.
